(57) **CLAIM**

The ornamental design for a bottle for a breast pump system as shown and described.

DESCRIPTION

FIG. 1 is a front view of a bottle for a breast pump system
FIG. 2 is a rear view thereof;

FIG. 3 is a right side view thereof;

FIG. 4 is a top view thereof;

FIG. 5 is a bottom view thereof; and,

FIG. 6 is a raised front perspective thereof.

The left side view substantially mirrors the right side view.
The dashed lines in the figures illustrate environmental structure and form no part of the claimed design.
